UNITED STATES PATENT OFFICE

2,533,874

FOLDING DISPLAY

Ned Burr, Chicago, Ill., assignor to Chicago Cardboard Company, Chicago, Ill., a corporation of Illinois

Application July 9, 1945, Serial No. 603,833

5 Claims. (Cl. 40—152.1)

1

This invention relates in general to a folding display of cardboard, or the like, and has more particular reference to parts which are connected for rotary or pivoted movement in the collapsing and distending of the display.

An important object of the invention is to provide a folding display with pivotally connected parts made of the material of the display itself.

A further object of the invention is to provide a spaced and pivoted floating piece for use in a folding display.

A still further object of the invention is to provide a folding display having panels supported at different angles and a folding part pivoted to one panel and adapted to make an angular connection with another panel.

A still further object of the invention is to provide a folding display having connected panels some of which are distended and held by rigidly attached means and others of which are connected by a rotatable part which is spaced from the panels and connected at an angle thereto.

Other objects of the invention will appear in the specification and will be apparent from the accompanying drawings in which:

Fig. 1 is a front view of a display in accordance with this invention in extended position;

Fig. 2 is a rear view of the display shown in Fig. 1;

Fig. 3 shows a blank of the display;

Fig. 4 is a perspective showing the rear of the folded display piece of Fig. 1;

Fig. 5 is a sectional view of the display as shown in Fig. 1;

Fig. 6 is a detail section taken on the line 6—6 of Fig. 2;

Fig. 7 is a perspective of the modified form of the display;

Fig. 8 is a sectional view taken on the lines 8—8 of Fig. 7;

Fig. 9 is a rear view of the easel as shown at Fig. 8;

Fig. 10 is a sectional view taken on the line 10—10 of Fig. 7;

Fig. 11 is a perspective of the display and holding box at the bottom of Fig. 7;

Fig. 12 is a section taken on the line 12—12 of Fig. 7;

Fig. 13 is a sectional view taken on the line 13—13 of Fig. 12; and

Fig. 14 illustrates a modification of the mounting means.

In folding displays of cardboard, and the like, it has been the practice to attach parts for floating

2

or rotary movement by means of eyelets or rivets so that one piece could be swung into the area of the other, in folding, thus reducing the folded size of the display to a minimum, and the parts 5 relatively moved or rotated in setting up or distending the display. As it is now difficult or impossible to obtain metal pivoting parts, a rotary support or pivot made up of the material of the display itself is highly desirable in order to provide folding displays which can be collapsed or folded into a minimum space for storage or shipment and readily extended and rotated in setting up the display.

The present invention overcomes these objections and difficulties, and provides an improved and novel form of pivoting connection for display parts in which one of the parts has a circular perforation or an opening and the other part has projections which fit into the perforation or opening and expand resiliently to hold the parts together for pivoting or rotary movement about the opening.

The outer faces of the display parts are usually printed to present a picture, a figure, a piece 15 of apparatus, and the like, which may have angularly disposed or offset portions to vary the pictorial or other representation. Rotary, movable, or boxlike parts and projections are frequently added to form a part of the display and 20 to provide an integral and interesting part of the composite design and structure which is presented.

Referring now more particularly to the drawings, a folding display comprising three connected sections is shown in Figures 1 to 6 having a main panel 16 and side panels 17 and 18 hinged thereto and foldable together in collapsing the display. Mounted upon one of the panels for rotative movement with respect thereto is a display piece 20 which is of a size to be contained within the area or outline of one of the panels as 16 when the display is folded, but which is adapted to extend across the hinge between the adjacent panels and even to overlap 40 the adjacent panel, when the display is extended. The mounting for the display piece 20 for rotating it with respect to the panel comprises an integral or separate hinged projection 21 with flexible hinged tabs 22 extending oppositely and 45 connected by an offsetting flexible hinge 23 made of the material of the projection, the tabs formed thereby being easily pressed together and inserted through an opening or perforation 25 in the panel, the hinges 23 forming chords across the opening 25, if circular, and the tabs 22 having

sufficient resilience tending to spread them outwardly to engage and retain the display piece in a rotary pivoted relation with respect to the panel.

At the other end of the display piece is a disengageable fastening means for attaching it to another panel. This may comprise a hinged projection 26 having a reduced tongue 27, adapted to be inserted through a slot 28 in the adjacent panel. The projection 26 may be somewhat angular or wedge-shaped so that the panel to which it is attached may be held at an angle to the other main panel 16 and the projection 21 at the other end of the display piece may be bent upon itself to offset it from the face of the panel 16 as shown more clearly in Fig. 5.

At the rear of the display is a support therefor comprising a flat folding easel 30 attaching the main panel 16 and having a transverse slot 31 near its upper end for engaging a tongue 32 projecting from a similar flat folding easel 33 attached to the adjacent panel and having a fold line 34 transversely thereof for collapsing it when disengaged from the easel 30 within the confines of the panel 18, when the entire display is to be folded.

In the form of the invention as shown by Figs. 7 to 13, a main panel 40 is connected to a side panel 41 by an intermediate offsetting panel 42.

At the back of the main panel 40 is a flat folding easel 43 and at the front is a bottom display box 44 secured to the main panel having connected hinged portions 45 and 46 with tongues 47 and 48 respectively for engaging a slot 49 in the intermediate panel 42 and a slot 50 in the main panel 40 for holding the box in distended supporting display position.

A rotatably movable display piece 51 has a pivoting connection through a perforation 52 in the side panel 41 comprising a hinged and foldable member 53 attached at its ends to the rear side of the piece 51, having opposite connecting sides 54 and opposite hinged tabs 55 connected by offsetting hinges 56, the tabs being inserted through the perforation 52 and holding the display piece rotatably in connection with the panel. At the other end of the display piece is a hinged offsetting plate 57 having an outer edge at an angle to the back of the piece 51 and having a tongue 58 projecting therefrom and engageable in a slot 59 in the main panel 40.

In the above form of the invention, the display box 44 serves to hold two of the panels in fixed angular position and the display piece holds the third panel at an angle to the other two with the display piece itself extending at a distance from all of the panels, but connecting them in angular display position.

When folded, the display piece is disconnected and swung into the area of the panel 41, the display box 44 is disconnected and folded upon a transverse fold line 39 within the area of the panel to which it is attached and the panels are folded together in compact relation to each other.

Instead of having the pivoting means attached to or formed integrally with the movable piece, the connection may be reversed as illustrated in Fig. 14. A panel 60 has a separate piece 61 attached thereto with opposite hinged projecting tabs 62 which are inserted through a perforation 63 at one end of an arm or other member 64 to be mounted thereon. This arm is rotated within the area or confines of the panel 60, but may be extended by rotation beyond the edge of the panel and may be attached to another panel as

shown and described or may be inserted through a slot 65 in the panel so that the outer or free end of the rotatable arm 64 is located on the face of the panel, the rotary mounting therefor being located on the back of the panel as shown.

Various other combinations and arrangements of the panels, the transverse display arm, the rotary mountings and the connections may be made without departing from the spirit and scope of the invention.

I claim:

1. In a folding display, a plurality of panels hinged together and extensible for display purposes, a movable piece contained within the area of one of the panels in folded position but extensible beyond the confines of one panel and across the fold line between the panels when the display is set up and extended, means forming a pivoting connection made integrally of the material of the piece and an opening in the panel itself at one end of the piece, and means forming a disengageable connection at the other end of the piece with one of the other panels of the display.
2. In a folding display comprising panels hinged consecutively together and a rotatable piece pivoted on one of the panels, the panel having a perforation and the piece having bendable tabs projecting therefrom at one end extending through the perforation and spacing the piece from the face of the perforation, the other end of the piece having a projecting angular tongue and the other connected panel having a slot to engage the tongue and to support the piece at an angle to the panels and spaced from the faces of the panels.
3. In a folding display, a pair of hinged panels and a movable display piece contained within the area of one of the panels when folded, but extending beyond the area of the panel when the display is extended, the cross piece and the panel having a pivoting mounting at one end of the piece comprising an opening in one of them, and resilient tabs projecting from the other through the opening and extending outwardly from the opening on the other side and a tongue and slot connection between the piece and the panel at the other end of the piece holding this end of the piece at an angle away from the panel.
4. A folding display comprising panels hinged together, a foldable easel at the back of one of the panels for supporting the display, a folding construction at the back connected to one of the panels and engageable with the easel of the other panel in distended relation for holding these panels in fixed position with respect to each other, a movable display piece pivoted to the front of one of the panels and rotatable to extend across the hinge connection between this panel and an adjacent free panel, and means forming a releasable connection between the free end of the piece and the last named panel for holding it inclined to the supporting panel.
5. In a folding display, a plurality of panels hinged together, a display piece rotatably connected to one of the panels and movable from within the area of this panel when folded to a position across the hinge line between it and an adjacent panel when the display is extended, a releasable connection between the free end of the display piece and the second panel, a foldable easel at the back of one panel and a foldable easel locking construction secured to the back of the adjacent hinged panel having a portion to extend across the hinge between it and the easel supporting panel to engage the easel thereof in dis-

tended position, the engagement of the easels holding their panel sections together in fixed straight line relation.
